INSULATOR SUPPORT SOCKET FOR
FLUORESCENT LIGHT TUBESJacob D. Jessup, Wichita Falls, Tex., assignor to Wayland
D. Keith, Wichita Falls, Tex.

Application August 4, 1953, Serial No. 372,313

4 Claims. (Cl. 339—52)

This invention relates to an insulator support socket for fluorescent light tubes, and particularly to a socket for utilizing fluorescent tubes for illumination, after the normal useful life thereof, as fluorescent lights has been spent.

Various gas filled tube lights, such as fluorescent lights that have a filament, such as bi-pin fluorescent lights which utilize a filament and a starter to initially heat the gas so as to place it in proper conductivity form, are now in use. The normal life of such tubes depends greatly on the number of "starts" of the fluorescent light, as it is primarily the starting of these lights that causes the greatest deterioration of the filament and governs or determines the life of such tubes as normal fluorescent lights.

Heretofore, it has been the practice to discard as useless, such tubes when the filaments thereof ceased to function.

In the present invention, a socket has been devised whereby these tubes, which have ceased to function as fluorescent lights, can be simply and effectively connected in end to end relation and subjected to high voltage, whereby a multiplicity of these tubes can be illuminated with satisfactory brilliance over a long period of time.

An object of this invention is to provide a tube support socket that will securely support the spent fluorescent tubes therein so they may be connected electrically in end to end relation.

Still another object of this invention is to provide a tube support socket which will hold the tubes in a fixed relation so all exposed contact portions thereof will be covered by insulation.

A still further object of this invention is to provide a tube support socket, the covering of which may be quickly attached and detached to permit the insertion or removal of the tubes therefrom.

With these objects in mind and others that will manifest themselves as the description proceeds, reference is to be had to the accompanying drawing in which like reference characters designate like parts in the several views thereof, in which:

Fig. 1 is an exploded perspective view of a tube support socket member and cover therefor;

Fig. 2 is an end view of the tube support socket member showing the cover and one tube element in place;

Fig. 3 is a sectional view taken substantially on the line 3—3 of Fig. 2 and showing a fragmentary end portion of two fluorescent bi-pin tubes in dashed outline;

Fig. 4 is a perspective view of a connector contact clip removed from the socket support member, and

Fig. 5 is a modified form of the socket showing how the tubes are connected together at right angles.

With more detailed reference to the drawing, the numeral 11 designates generally a socket member which is adapted to receive a cap generally designated at 12, so as to hold the fluorescent tube, generally designated at 13, securely, which tube and connections are insulated so as to prevent leakage of electricity to the member on

2

which the socket is mounted. The socket member 11 has a base 14 which is of suitable insulating material, such as plastic, hard rubber, porcelain, glass or the like. The base 14 has holes 15 formed therein to enable the socket member to be secured to a mounting strip, building, or the like. A stem, which is made of the same insulating material as the base and is integral therewith, and is designated at 16, extends upward from the socket member 11 and has a semi-cylindrical tube receiving member 17, 10 of the same insulating material, on the upper end thereof.

A pair of ribs 18, of the same insulating material, are formed integral with the stem and base and form a brace for the semi-cylindrical member 17. An insulating projection 19 is mounted mediate the sides of the semi-cylindrical member 17 and has a connector clip 20 secured on the top thereof by a screw 21. The connector clip 20 has upstanding prongs 22 that form U-shaped sockets to receive the pins of bi-pin tubes generally designated at 13. The pairs of upstanding prongs 22 on each side of the clip 20 are spaced apart so a ground wire may be connected to the screw 21, which ground wire may pass between the upstanding prongs 22 and out through a hole 23 which is formed in the side of the semi-cylindrical member 17, so as to enable the utilization of the socket to give a midpoint ground substantially as shown in Fig. 7, or other electrical connection.

The semi-cylindrical portion 17 is concave and is of such size as to receive the particular tubes that are being used therein. The longitudinal edges have out-turned lips 24 at each end thereof that are adapted to complementarily engage with in-turned lip 25 formed along each of the longitudinal edges on the cap member 12. A notch 27 is formed mediate each longitudinally aligned pair of ribs 24, which notch is adapted to complementarily receive the rib 28 formed mediate the length of the cap 12, which ribs prevent relative longitudinal movement of the cap and the semi-cylindrical member 17. A spring 29 is secured to the cap 12 by means of a screw 30 mediate the sides and longitudinally spaced mediate the ends so that the spring will engage the sides of the tubes 13 to hold the pins 13a of the respective tubes 13 securely within U-sockets of the clip 20, as will best be seen in dashed outline in Fig. 3.

It is to be pointed out that the base 14, stem 16, semi-cylindrical member 17, ribs 18, and projections 19 are preferably formed integral of a single piece of material such as plastic, phenolic resin, hard rubber, porcelain, glass or other suitable insulating material and that the cap 12 is formed of the same suitable insulating material, 50 and that the cap will complementarily engage the bottom portion 11, which is sufficiently resilient so that when pressed downward, the sloping edges of the in-turned lip 25 will complementarily engage the out-turned lip 24. The slope on the respective lips is such that they may be pressed together easily, but will require a tool for the removal of the cap, thereby providing a sufficiently tight fitting cover to prevent accidental misplacement of the cap, and the cap has sufficient insulating properties to prevent leakage of electricity therethrough, as might cause injury 55 to one coming in contact with the device.

The socket and cap members 11—12, as shown in Figs. 1 through 4, enables tubes 13 to be joined in axial alignment.

The type of socket member, as shown in Fig. 5 is 65 similar in all respects to the socket as shown in Figs. 1 through 4, except it is so arranged as to enable the tubes 13 to be joined at an angle other than a straight angle. The socket illustrated shows the tubes 13 to be joined at a ninety degree angle, however this is merely 70 illustrative, and it is to be understood that the tubes may be joined at any desired angle.

In this form of the device, the socket member is desig-

nated generally by the numeral 31, and has a cap 32. The socket member 31 has a base 34, a stem 36, a concave semi-cylindrical member 37 and upstanding projections 39, within the concave, semi-cylindrical member 37, which projections receive a clip member 40 thereon. The component parts 34, 36, 37 and 39 are made of a suitable insulating material, similar to the socket as described above. Holes 35 are formed in each side of the base 34, which enables the securing of the socket member to a mounting strip or to a building or the like, in the same manner as for the above described socket. Ribs 38 are provided on the stem 36, which ribs are also joined to the base 34 and to the semi-cylindrical member 37. The clip 40 is secured in place by means of screws 41 and the upstanding projections 42, together with the down-turned sides of clip 40, form U-sockets to receive the bi-pins 13a of the respective tubes 13, which projections preferably press inwardly to resiliently engage the pins so as to make a secure contact to prevent arcing or burning of the clip. A hole 43 is provided in the side of the semi-cylindrical member 37 to enable a ground wire to be passed therethrough and secured beneath one of the screws 41 so as to enable the socket to be used as a mid-point ground in the circuit as shown in Fig. 7.

The semi-cylindrical member 37 has an out-turned lip 44 formed on the upper edges to complementarily engage an inturned lip 45 formed on the lower edge of the cap 32. A notch 47 is formed between lip 44 on each side thereof to receive a rib 48 therebetween so as to prevent relative movement between the cap 32 and the semi-cylindrical member 37. A spring 49 is secured to the cover 32 so as to hold the fluorescent tube 13 securely within the sockets of the clip 40.

If so desired, an annular resilient gasket R may be fitted in each inner end of each of the sockets to exclude moisture from entering the sockets 31-32. It is preferable to use the sockets within the circuits illustrated in Figs. 6 and 7, and although one pin is sufficient to serve as an electrode or conductor into the tube, the sockets described above enable both pins to be securely mounted in place and in event one is defective, the other will automatically serve as an electrode, or if both pins provide conductivity of electricity into the tube, each will serve as an electrode with substantially the same degree of efficiency as a single electrode.

While the invention has been described in some detail both for mounting the tubes in end to end relation longitudinally or at an angle with respect to each other, it is to be understood that changes may be made in the minor details of construction without departing from the spirit of the invention or the scope of the appended claims.

Having thus described the invention, what is claimed is:

1. An insulator support socket for bi-pin fluorescent light tubes, comprising a base, a stem rising from said base, a body on the upper end of said stem, which body has an upwardly facing recess formed therein, a metallic, 5 pin-receiving clip mounted on said body within said recess and receiving both pins of said tubes in electrical short circuit relation, a cap complementarily engageable with said body for maintaining said tubes within said recess, and a spring mounted in said cap for resiliently maintaining said cap on said body.

2. An insulator support socket for adjacent ends of a pair of bi-pin fluorescent light tubes comprising a base, a stem rising from said base, an open end semi-cylindrical body on the upper end of said stem, which body has a 15 unitary, metallic conductor element therein comprising a clip having a pair of upwardly facing recesses formed therein and spaced apart and receiving two pairs of bi-pin fluorescent lamp terminal pins in inverse end to end electrical short circuit relation, and a cap member adapted to complementarily engage said support socket for maintaining said tubes within the recesses of said conductor.

3. An insulator support socket for bi-pin fluorescent light tubes, comprising a base, a stem rising from said base, a body on the upper end of said stem and having an upwardly facing recess formed therein of less than a straight angle, a one-piece metallic member mounted on said body within said recess and having at least two 25 spring arms forming pin-receiving sockets spaced apart linearly and being adapted to receive both pins of said tubes in electrical short circuit relation, and means for maintaining said tubes within said recess.

4. An insulator support socket for bi-pin fluorescent light tubes, comprising a base, a stem rising from said base, a semi-cylindrical body mounted on the upper end 35 of the stem, said body having an upwardly facing recess formed therein of less than a straight angle, a one-piece metallic pin-receiving clip mounted on said body within said recess and having at least two bent arms forming pin-receiving sockets and being adapted to receive both pins of said tubes in electrical short circuit relation, and a complementary cap detachably secured to said body for maintaining said tubes within said recess.
